UNITED STATES PATENT OFFICE.

LOUIS J. W. WALL, OF ST. LOUIS, MISSOURI.

DESIGN FOR A PATTERN FOR PAPER.

SPECIFICATION forming part of Design No. 28,712, dated May 24, 1898.

Application filed December 9, 1897. Serial No. 661,325. Term of patent 14 years.

To all whom it may concern:

Be it known that I, LOUIS J. W. WALL, a citizen of the United States, residing in the city of St. Louis and State of Missouri, have ⁵ invented and produced a new and original Design for a Pattern for Writing and Printing Paper, of which the following is a specification.

In the accompanying drawing the double o lines indicate my design, while the fine straight lines indicate a tinted paper bearing my design.

In my design two slightly-curved parallel lines of even length are connected at one end ⁵ by a semicircular curve. Springing from the same end of each of these lines is a like semicircular curve on the side opposite the first-mentioned curve. Each of these last-mentioned curves is continued in a slightly-curved o line parallel with but extending slightly be-

yond the two intermediate lines. The uppermost line is continued downwardly in a curve consisting of two semicircles joined at a cusp and corresponding with the like curves at the opposite ends of the lines.

The figure just described is repeated in a series of rows, the figures in the several rows being arranged to form straight columns, and the pattern thus produced constitutes my design. ²⁵

Having described my invention, what I claim as new, and desire to secure by Letters Patent, is—

The design for a pattern for paper substantially as herein shown and described. ³⁰

LOUIS J. W. WALL.
